(57) **CLAIM**

The ornamental design for a connector grip, as shown and described.

DESCRIPTION

A portion of the disclosure of this design patent document contains material to which a claim of copyright protection is made. The copyright owner has no objection to the facsimile reproduction of the patent document or the patent disclosure as it appears in the U.S. Patent and Trademark office file or records, but reserves all other rights.

FIG. 1 is a perspective view of a connector grip, in accordance with the present invention.

FIG. 2 is another perspective view thereof.

FIG. 3 is a top view thereof.

FIG. 4 is a frontal view thereof; and,

FIG. 5 is another top view thereof.

The broken lines showing the environment in FIGS. 1 & 5 are for illustrative purposes only and form no part of the claimed design.
